UNITED STATES PATENT OFFICE

ARTHUR G. CLARK, OF ST. PAUL, MINNESOTA, ASSIGNOR OF ONE-THIRD TO ALEXANDER C. ROBARGE AND ONE-THIRD TO GEORGE E. SNELL, BOTH OF ST. PAUL, MINNESOTA

CONCRETE BUILDING STRUCTURE

Application filed October 27, 1927. Serial No. 229,109.

This invention relates to concrete building structure and especially to wall structure formed from concrete or other plastic self-hardening material.

5 It is an object of my invention to provide simple but highly efficient wall structure for buildings, capable of being quickly and easily set up and having a maximum strength.

A further object is to provide wall structure combining a multiplicity of prepared building units and column structure formed and set up in said units, said units being positively locked together and with said column structure against lateral or longitudinal displacement.

15 Another object is to provide concrete wall structure including concrete columns and a plurality of building units wherein said columns are formed, said structure being capable of wide variation to meet various tensile requirements without varying the size or structure of the building units.

A still further object is to provide in structure of the class above described, building units adapted to be laid in the manner of bricks, and also adapted to form a plurality of molds for concrete columns, said columns so formed being positively locked to said building units and the abutting ends of said building units being locked with said columns against longitudinal and lateral displacement.

These and other objects and advantages of the invention will be apparent from the following description made in connection with the accompanying drawings wherein like reference characters refer to similar parts throughout the several views and in which,

Fig. 1 is a side elevation of a concrete wall embodying my invention;

Fig. 2 is a horizontal section taken on the line 2—2 of Fig. 1;

Fig. 3 is a vertical section taken on the line 3—3 of Fig. 1, showing the manner in which the vertical sides of the building units interlock and also the manner in which the top of the wall may be finished off;

Fig. 4 is a section taken on the line 4—4 of Fig. 3, showing the manner in which the vertical ribs of the building units interlock;

Fig. 5 is a bottom perspective view of one of the building units; and

Fig. 6 is a horizontal section of the corner formed by two intersecting walls wherein the inwardly disposed ends of the building units are spaced apart some distance but nevertheless locked to the corner column and wherein a corner column of considerable cross section is employed.

The building units which I employ, as best shown in Fig. 5, are preferably formed or molded from concrete although other self-hardening plastic material may be used. Each unit comprises a pair of elongated substantially parallel sides 7 connected and spaced apart by a plurality of transversely disposed partitions or ribs. As illustrated, ribs 8 are disposed adjacent the respective ends of sides 7, set inwardly slightly therefrom, while a pair of spaced ribs 9 are disposed in the medial portion of the unit preferably being spaced closer together than the distance from either thereof to the end ribs 8. The base and top edges of the side walls of unit 7 are oppositely and longitudinally rabbeted in the manner of ship lap. As illustrated the bottom edge 7a is longitudinally rabbeted on the inside, while the top edge 7b is longitudinally rabbeted on the outside. It will be remembered that Fig. 5 shows a bottom perspective view of the unit. It will be apparent that when the units are laid one above the other, the edges will be lapped as clearly illustrated in Fig. 3. As shown, the distance from the ribs 8 to the ends of the sides 7 is equal to one-half the distance between the medial ribs 9.

The bottom edges of the partitions or ribs 8 and 9 of the unit are concave or recessed at 8a and 9a respectively, while the upper edges 8b and 9b respectively of said ribs are convex in shape projecting above the top edges of the sides 7. Said concave and convex edges of two units fit in the manner illustrated in Fig. 4, assisting to interlock the successive layers of units against both longitudinal and lateral displacement.

It will also be seen that the extremities of sides 7 of the unit diverge having slightly inclined locking surfaces 7c extending from

the end partitions 8 to the extremities of sides 7 and being disposed inwardly of the unit. The abutment ends of sides 7 are beveled at 7d and 7e respectively, said beveled surfaces 7d and 7e being disposed parallel rather than symmetrically.

As illustrated in Figs. 1, 2 and 6, my wall structure is formed by the combination of a multiplicity of my building units previously described, with columns or studding molded by portions of said building units and securely locked therewith. As illustrated, the footing or foundation F is first formed and the building units are laid in alternately staggered rows, staggered on the half to cause partitions 9 of one unit to be vertically aligned and to register with the adjacent partitions 8 of vertically consecutive units. This results in the formation of a hollow wall having vertical passages extending from top to bottom, alternate passages being of equal dimensions and adjacent passages being of different dimensions. Said vertical passages are filled by the columns or studding S and either the larger or smaller passages may be utilized to mold the columns to securely lock the building units together and to securely lock the building units with the columns. It is only necessary to pour soft concrete into the passages where columns are desired, suitable reinforcing irons or rods R being inserted. It will be seen that where two horizontally aligned building units abut and the column extends through the passage formed by the abutting ends, that the inclined or diverging locking surfaces 7c dovetail with inclined surfaces or edges of the column formed. The abutting units, therefore, are locked to the column against longitudinal displacement from each other.

When a corner is formed in the building structure, as shown in Figs. 2 and 3, the ends of the walls defining said corner may be disposed in close relation as shown in Fig. 2, or may be spaced apart as shown in Fig. 6. In Fig. 2 the extremities of the inner sides 7 of the units abut, while the extremities of the outer sides, of course, are spaced some distance apart. To form the corner column indicated by the letter C, it is necessary to provide an outer angular mold M shown in dotted lines and this mold may be formed by merely boarding up the sides of the wall and suitably bracing the same. Concrete in soft state is then poured into the vertical mold formed by the boards M and the extremities of the two walls and suitable reinforcing irons R are disposed in substantially vertical position extending from the top to the bottom of the column.

It will be noticed that the locking surfaces 7c at the ends of the several units forming the two walls dovetail or interlock with the corner column C to prevent longitudinal displacement of said walls from said column.

The top of my wall may be finished off by applying horizontally a strip of metal lath or screening 10 to the edges of the top layer of building units and laying a layer of concrete 11 above said metal lath.

When the building units are laid in staggered relation it will be seen that the lapped edges of two successive layers of units overlap and that the concave and convex horizontal edges of the ribs 8 and 9 are seated and interlocked, whereby building units will be securely locked against lateral displacement before the columns S and C are formed. The columns S and C, of course, positively lock the units against both lateral and longitudinal displacement and in combination with the multiplicity of units form a wall of maximum strength for the amount of material used. While in the drawings the smaller columns or studding S are formed in the smaller vertical passages of the building units, it will be obvious that said columns may be poured and formed in the larger vertical passages spaced apart between smaller passages. It is further apparent that if it is desirable to space the columns S farther apart various spacings may be effected by utilizing any desired combination of vertical passages for the forming of the columns.

The beveled ends of the building units assist in further locking abutting units together against lateral displacement when the wall is laid as shown in Figs. 2 and 6.

I prefer to provide half building units as well as the complete building units, although if desired the complete units may be broken in half to finish off the ends of the wall. As shown in Fig. 6, the half units are provided having at either end the diverging, inclined, interlocking surfaces 7c.

In laying the walls of a building the units may be either laid to the full height of the walls desired, the reinforcements R inserted and the columns then poured, or the units may be laid to the height of relatively short reinforcements varying from three to twenty feet, the reinforcements disposed in the desired passage to be utilized and the columns poured to the height of the wall laid and thereafter the units may be laid to a new height substantially equal to twice the first, and the column passages again filled with soft concrete. The latter method may be preferable in erecting office buildings or other structures of considerable height.

From the foregoing description it will be seen that I have invented a highly efficient concrete building structure combining maximum strength with minimum material and capable of being manufactured at low cost. The novel building units provided may be employed to form co-operative columns disposed or spaced in different manners and of

different cross section. The units are locked with each other in several different ways against both longitudinal and lateral displacement and when the columns are formed 5 the entire structure is permanently interlocked and the columns and building units co-operate to produce a unitary result, namely, the formation of a highly efficient building.

10 It will, of course, be understood that various changes may be made in the form, details, arrangement and proportions of the parts without departing from the scope of the invention.

15 What I claim is:

1. An integral building unit comprising a pair of vertical parallel sides, two pairs of transverse partitions connecting said sides and extending approximately the full height 20 thereof, the end partitions of the pairs being inset from the ends of the sides a distance equal to one-half of the distance between the inner partition of the two pairs, the upper and lower edges of the sides being reversely 25 rabbeted to lap with edges of units in successive layers preventing lateral displacement of said layers, said sides having dove-tail ends at their inward surfaces adapted to interlock with a concrete column partially 30 molded thereby.

2. An integral building unit comprising a pair of vertical parallel sides, two pairs of transverse partitions connecting said sides and extending approximately the full height 35 thereof, the end partitions of the pairs being inset from the ends of the sides a distance equal to one-half of the distance between the inner partition of the two pairs, means at the upper and lower edges of said sides for preventing lateral displacement of successive 40 layers of units, said sides having dove-tail ends at their inward surfaces to interlock with a concrete column partially mounted thereby.

45 In testimony whereof I affix my signature.
ARTHUR G. CLARK.
